UNITED STATES PATENT OFFICE.

HERALD P. ARNT, OF LAKESIDE, OHIO.

SPRINKLING-HOSE SUPPORT.

Application filed March 25, 1922. Serial No. 546,734.

My invention relates to a sprinkling hose support adapted for instance, to carry and direct the nozzle end of a garden hose.

I am well aware that the art of water sprinklers is highly developed, but have realized that the spraying devices which spread streams of water over a circular area are frequently unsatisfactory when it is desired to sprinkle ground space defined by a straight line such as along a curb or sidewalk or along a neighbor's line. The same is true when it is desired to concentrate the water flow upon an elongated flower bed. The reason whirling sprinklers are unsatisfactory is because a large percent of the water discharged therefrom may be considered wasted under the circumstances I have just enumerated, because it becomes deposited either upon a street, sidewalk or neighbor property.

Accordingly, the object of my invention has been the design of a support which will be durable, sufficiently economical of manufacture, easily portable and very readily adjusted by a single securing means so as both to clamp different sized hose and to vary the inclination at which the spray nozzle is held. Besides, the structure I have designed permits of having its component elements readily disassembled thereby allowing the parts to be more compactly shipped. My support includes a weighted base and a detachable pedestal which carries an adjustable hose clamp intended to bind the hose near the discharge nozzle and to be fixed in various angular positions so as to direct the stream of water lengthwise of a bordering ground area which it is desired to moisten.

Advertising to the drawings:

Figure I is a side elevation of a structure embodying my invention carrying the discharged end of a hose.

Figure II is an enlarged side elevation of Figure I, portions of the hose and nozzle being shown in dotted lines.

Figure III is a section on line III—III of Figure II.

Figure IV is a section on line IV—IV of Figure II.

Figure V is an end view showing the hose clamp in its closed position.

Figure VI is a similar view showing the hose clamp in its open position.

Figure VII is a side view of one detail

together with a fragmentary view of an attached part.

Figures VIII and IX are a side view and an end view respectively of one of the clamping shells.

Figures X and XI are side views of a bolt viewed from right angularly related directions.

A weighted base 1 which as shown is a circular casting of spider construction including four upwardly inclined radial arms 2 adapted to support a central boss 3 in a position such that its bottom is elevated with respect to the bottom of the annular rim 1 as indicated by the dotted lines in Figure II. The boss 3 is fashioned with a four sided bore 4 in which is fitted the squared lower end 5 of a pedestal, in such a manner that the extremity projects beyond the bottom of the part 3 where it is provided with a hole 6 for the reception of a cotter pin 7. In this way the pedestal 5 and base 1 are detachably connected.

The upper end 8 of the pedestal is widened in one direction and narrowed in a transverse direction, and is provided near its top with a hole 9 extending in the direction in which the shortest dimension is to be measured. A bolt 10, shown in detail in Figures X and XI, includes a threaded end 11 and an intermediate portion of its shank fashioned with oppositely disposed flat sides 12. The other end of the bolt detachably carries a head 13 fixed in any feasible manner to the shank, though as exemplified in the drawings, locked thereto by means of a pin 14. The head 13 is fashioned on the side facing the threaded end 11 with a cylindrical surface 15, the purpose of which will hereinafter become evident. A clamping washer 16 loosely carried by the bolt is likewise fashioned with a cylindrical surface 17 intended to be opposed to the surface 15. A wing nut 18 is applied to the threads 11 and serves either to force the washer 16 toward the head 13 or when loosened permits the washer 16 to move away from the head 13 as will be readily understood.

A pair of concavo-convex hose-clamping shells 19 and 20 have their upper ends include arcuate sections with their concave surfaces opposed and purposed to envelop and clamp a hose. The lower ends 21 and 22 of the shells have their convex surfaces opposed and are fashioned each with a cross

slot 23 through which the smaller unthreaded end of the bolt loosely extends. The slots 23 are longer than the diameter of the shank of the bolt, so that the shells may be reciprocably adjusted crosswise of as well as along the bolt shank, the flat sides 12 of the bolt meanwhile guiding the elongated straight sides of the slots 23. It will be observed that the concavo-convex lower ends 21 and 22 of the shells conform in curvature to the surfaces 16 and 15, thereby enabling a limited adjustment of the shells 19 and 20 relatively to each other, without, however, permitting any considerable movement of the shells in a direction around the bolt owing to the engagement of the flat sides 12 with opposite sides of the slots 23 as earlier mentioned. However, the two shells 19 and 20 may be turned in unison with the bolt when the latter is permitted to turn in the hole 9 consequent upon a loosening of the wing nut 18 thereby permitting angular adjustment of the clamping shells with respect to the pedestal. A hose 24 is shown clamped within the shells 19 and 20 in Figure V and the hose is shown in Figures I and II to carry a nozzle 25. An especial feature of my invention is that a tightening movement imparted to the wing nut 18 simultaneously fixes not only the shells 19 and 20 with respect to each other but also the bolt 10 with respect to the pedestal thereby both simplifying and expediting a fixing of the parts in any desired position of adjustment. In operation, after the wing nut has been unscrewed a suitable distance the connection of the parts carried by the top of the pedestal will be so loosened as to enable separation of the shells 19 and 20, or permit of causing them to describe arcs as a rocking movement within an axial plane of the bolt or permit of effecting a turning movement of both shells together with the bolt within the hole 9. After the hose 24 has been inserted between the upper ends 19 and 20 and while the latter are held at the desired inclination, the wing nut 18 may be speedily tightened to simultaneously bind all the parts together.

50 I claim:—

1. A device of the character described comprising the combination of a support, a bolt carried thereby and having a shank fashioned with a flat side, and clamping

mechanism including a pair of clamping elements carried by said bolt and one of which has a curved area fashioned with an elongated aperture through which said bolt projects, the arrangement permitting said curved element to be shifted nearer to or farther from the other element, and a nut for fixing the parts in desired position. 55

2. A device of the character described comprising the combination of a support, a bolt mounted to turn thereon and having a shank fashioned with oppositely disposed flat sides, a pair of clamping elements each fashioned with an elongated aperture having oppositely disposed straight edges adapted to be engaged by the flat sides of 70 said bolt which passes through the apertures in said elements, the arrangement being such as to permit reciprocal adjustment while being locked against relative turning movement, and means for fixing the parts 75 with respect to said support and each other.

3. A device of the character described comprising the combination of a support, a bolt carried thereby, a pair of clamping elements each fashioned with an elongated 80 aperture through which said bolt loosely passes, the arrangement being such as to permit reciprocal adjustment of said elements both along and crosswise of said bolt, and means for fixing the parts in a chosen 85 position of adjustment.

4. A device of the character described comprising the combination of a support, a bolt carried thereby and having a head fashioned with a curved surface, a pair of 90 clamping elements each having a complementally curved surface, the latter being fashioned each with an elongated aperture, said bolt being loosely passed through said apertures, the arrangement being such as 95 to permit reciprocal adjustment of said elements both along and crosswise of said bolt, a washer fashioned with a curved surface opposed to the corresponding bolt head surface and adapted to cooperate therewith to 100 clamp said elements against said support and a nut for drawing said head and nut toward each other to bind the parts together.

Signed by me, this 24th day of March, 105
1922.

HERALD P. ARNT.
